(57) **CLAIM**

The ornamental design for a cap for a container, as shown and described.

DESCRIPTION

FIG. 1 is a front, perspective view of a cap for a container according to the new design shown mounted on a container in an open state;

FIG. 2 is rear, perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front, perspective view of a cap for a container according to the new design shown in an open state and free of any container;

FIG. 10 is rear, perspective view thereof;

FIG. 11 is a front view thereof;

FIG. 12 is a rear view thereof;

FIG. 13 is a left side view thereof;

FIG. 14 is a right side view thereof;

FIG. 15 is a top view thereof; and,

FIG. 16 is a bottom view thereof.

All broken lines shown in the drawings are for environmental purposes only and form no part of the claimed design.
